PROCESS OF MAKING SLIVERS FOR USE IN
PADDINGJesse A. Hunt, Collegepark, Ga., assignor to Egan
Cotton Mills, Atlanta, Ga., a corporation of
Georgia

Application January 23, 1933, Serial No. 653,157

3 Claims. (Cl. 19—145)

This invention relates to slivers for use in the manufacture of padding for laundry machines of the type in which the slivers comprise a core of more or less tough resilient fibrous material with a veneering or covering of soft fluffy material such as more highly processed cotton, or asbestos, wool or the like, and in which the padding comprises a plurality of layers of slivers or roving knitted together, and to the process of, and apparatus for, producing the same.

One of the principal objects of the invention is to provide a process of producing a sliver which when knitted into a padding will result in a padding of uniform thickness and weight throughout its length and breadth, the sliver having a central core of resilient fibers covered with fibrous material of different characteristics than the core and such as will present a smooth and even surface in the softness and parallelism of the covering or surface fibers, which surface fibers may be "comber" cotton, wool (or asbestos where extreme heat and wear-resisting qualities are required), or the like.

Another object of the invention is to provide an efficient and economical process whereby the fibrous materials of different characteristics to form the core and the veneer or covering of the sliver, respectively, may be run through a card simultaneously and delivered therefrom in a condition in which the core material is enveloped within the veneering or covering and encased thereby, and in which a sliver of uniform size, evenness and weight throughout its length is produced.

Another object of the invention is to provide a method in which laps of fibrous materials of different characteristics, one adapted to comprise the core, and the other adapted to comprise the covering or veneer of the sliver, are formed on pickers, the laps being divided on the pickers into a plurality of longitudinal strips, strips of the different materials being assembled on each of a plurality of lap sticks with a strip of core material arranged edge to edge and between strips of veneering material, the materials so assembled being fed from the lap sticks in a plurality of overlapping layers through a card, whereby the plurality of superimposed layers are transformed into a web having a central portion or zone of the core material flanked on each side by a portion or zone of the veneering material, the web as it is delivered from the card being divided into sections longitudinally, each section comprising a portion of the core material and a contiguous portion of the veneering material, the sections

as they are delivered from the card being drawn in opposite directions from the card and being simultaneously twisted with the core material enveloped within the veneering material. In connection with the object of the invention outlined above, I have found that by assembling rows of the strips of different materials edge to edge on the lap sticks, and by superimposing on the travelling apron of a card in a plurality of layers, the strips from a plurality of the lap sticks, a sliver is delivered from the card which is extremely even in the distribution of the materials of both the core and the veneer, is free of lumpiness, and is uniform in weight and size throughout its length, to a degree unattainable in other processes which I have tested known to the art, and results in a much better finished product.

A further object of the invention is to provide in combination with the mechanism of a picker, a series of pivoted and weighted levers provided with rotatable knives co-operating with an extremely hard calender roll over which the lap runs, whereby to cut the lap, whether composed of cotton, wool, asbestos, or other material, into the desired number and width of strips, the construction being such that the fibers of the lap are cleanly cut and no indentations are made by the knives on the roll, the knives being so mounted as to be easily removed for sharpening.

Another object of the invention is to provide a padding in which the layers of slivers of roving are composed of a core of a material having the characteristics of remaining resilient under the conditions of pressure, heat and vapor to which such paddings are subjected when in use on laundry machines, such as jute, flax, low grade cotton, ramie, wool, etc., and which has not been processed to a great extent, but in which the fibers are preferably in a state of intertanglement and intermixture, and in which the veneering or covering is composed of more highly processed, relatively fluffy, fibrous material adapted to withstand the heat to which the padding is subjected in use, such as asbestos, and in which the fibers are arranged in substantially parallel relationship.

With these and other objects in view which will appear more fully as the description proceeds, reference is made to the accompanying drawings, in which,

Figure 1 represents a front elevational view partly broken away, of a picker showing a lap of material being formed therein and being divided into strips.

Figure 2 represents a side elevational view of

Figure 1, illustrating the calender rolls and lap in dotted lines with the cutting knives in operative position.

Figure 3 represents a fragmentary plan view of the apron end of a card, illustrating the travelling apron, and an assembly of lap sticks on the mechanism with the rolls of assembled lap strips mounted on the sticks and illustrating the manner of delivering the assembled lap strips in overlapping relationship into the card.

Figure 4 represents a fragmentary end view of the doffing end of the card.

Figure 5 represents an elevational view of the wind-break of the card removed therefrom showing the web divider attached thereto.

Figure 6 represents an end view of the wind-break illustrated in Figure 5.

Figure 7 represents a view in perspective of a portion of a laundry padding made in accordance with the invention.

Referring more particularly to the drawings, the picker 2, illustrated in Figures 1 and 2, is provided with a shaft 1 bolted to the frame side of the picker by the cap screw 3, and on the shaft 25 is mounted a plurality of curved levers 4 freely journaled at one end on the shaft and maintained in adjusted spaced relationship with reference to each other by means of the set collars 5. Arms 6 are provided, one for each lever and at their inner ends may be forked and bolted between the sides of the curved levers 4 as at 7-7, weights 8 and 8' being slidably mounted on the arms and held in adjusted position by means of set screws 9.

The levers 4 at their outer ends have mounted 35 between their sides rotatable knives 10, which are mounted in anti-friction bearings 11 in such manner that the knives can be removed by releasing the screws 12 and taking off the side cover plates 13 which retain the bearings in position. 40 The levers are so positioned that the rotatable knives are adapted when the levers are in operative position, to bear against the fibrous lap 14 where the same runs over one of the calender rolls 15, and the weights are so adjusted as to bring sufficient pressure to bear on the knives to 45 completely cut entirely through the fibers of the lap as the latter moves forward and around the roll 15. The latter is made of material of such hardness as to resist the cutting action of the knives, so that the latter will not mar the surface 50 of the roll except under long continued use, in which case, the roll can be removed and re-surfaced. The levers are so positioned that they may be moved upwardly and around the pivotal 55 point afforded by the shaft 1 so as to swing the knives away from the roll and allow access to the latter and to the lap being formed in the picker, should occasion demand. It will be understood 60 that the material being fed through the picker upon different occasions may be of different texture and characteristics, but by properly adjusting the weights upon the arms 6 of the levers, the correct pressure can be brought upon the knives to cleanly cut the lap into a plurality of strips 65 as illustrated, without bringing undue pressure to bear against the roll. It will also be understood that the levers, and hence the knives are adjustable longitudinally of the rod 1, and that one or more of them may, if desired, be raised 70 up out of operative position, while the others are left in operative position, so that the lap can be divided into any desired number and width of sections as it runs through the picker.

In carrying out my process it will be understood 75 that a number of pickers may be used, and the

material to form the core of the slivers, such for instance, as low grade slightly processed cotton may be run through one of the pickers and thus formed into a lap which is divided into strips as the lap passes through the picker, while the material to form the veneer or covering of the sliver, such as asbestos fiber is being run through another picker formed into a lap and divided by the knives of the picker into strips.

Strips of the laps of different materials produced from different pickers, are then assembled edge to edge in rolled condition on each of a plurality of lap sticks 20, as indicated in Figure 3, two strips 17 of the laps which have been made of material for the veneering of the slivers, such as asbestos, "comber" cotton, or other suitable material, being placed at opposite sides of a strip 18 of a lap formed of material which will comprise the core of the sliver, such as low grade cotton, jute, etc. In the arrangement shown in Figure 3, it will be observed that the strips 17 of the veneering material are half as wide as the intermediate strip 18 of the core material. The lap strips thus assembled make up a roll of a width to correspond to the width of the carrier 25 apron 19 of the card (the doffer end of which is illustrated in Figure 4), and it will be observed that a plurality of sticks having the assembled lap strips thereon, are arranged on the machine, and the materials from the several lap sticks are 30 fed by the apron in the direction indicated by the arrows in a plurality of superimposed layers into the card.

The card acts upon the superimposed laps to transform them into a single web which emerges 35 from the doffer end of the card, and which, by reason of the superimposition of a plurality of laps at the feed end of the card, comes out in a sheet of substantially uniform thickness and continuity, with the longitudinal central portion or 40 zone of the web comprising the core material of the sliver and the longitudinal side portions or zones of the web comprising the veneering or covering material. Adjacent the doffer end of the card, is arranged a web divider 21 in the form of a strip of metal attached to the windbreaker 21' of the card, which divides the web longitudinally at its center, so that as the doffing comb 22 removes the web from the doffing cylinder 23, the web is divided into strips, each of which comprises two different grades of materials 18' and 17', respectively, the former of which has been carded from the superimposed layers of the core material 18 which has been fed into the card, and the latter of which has been carded from the 55 superimposed layers of veneering or covering material 17. As the divided strips emerge from the delivery end of the card they are rolled up and supported by the web-supporting cylinder 24, and drawn in opposite directions toward the sides of the machine by the rollers 28 and 29, respectively, and through the twister trumpets 27. As the sections of the web pass from the card along the roller, the trumpets exercise a twisting action on the web section, which results in the core material 18' being completely and uniformly enveloped within the covering material 17', so that the sections of the web emerge from the trumpets as at 30 in the form of a uniform sliver or roving having a core of resilient relatively slightly processed material, and an enveloping covering or veneer of asbestos, or other material of more highly processed character than the core.

The roving thus formed is eventually assembled in a succession of plies 25, knitted together as at 75

26, to form a padding for laundry machines. In the padding the layers of slivers or roving are composed of a core 18^a surrounded by a veneering 17^a of material differing in quality and kind and characteristics, from the material which comprises the core. The material of the core such as jute, flax, low grade cotton, ramie, wool, etc., is of a high natural resiliency relative to the material of the veneering (and relative to the cotton used in making paddings in the art at present), such as will make it tend to expand after having been compressed, and the fibers of the core are preferably in a state of interentanglement and intermixture, differing from those of the veneering, which latter as a result of the milling operations through which it has passed previous to the introduction of the material into the picker are in a more highly processed condition and in substantially parallel relationship. The veneering may take the form of "comber" cotton in the condition in which it comes from the last carding operation used in the processing of the cotton, so that the roving presents an external appearance similar to that of the high grade cotton which has heretofore been used in the art in making the entire roving. This veneering of finished cotton surrounds the more resilient and interentangled fibrous core of the roving, the core thus acting as an agency which imparts to the sliver, and to the padding, when the latter has been formed, a degree of resiliency and toughness which withstands to a marked extent, the conditions of heat, pressure and moisture to which the padding is subjected while in use. The core, when it is composed of cotton, may be made of a low grade cotton which has been processed only sufficiently to allow it to be formed into a sliver or roving, and consequently may contain some impurities or foreign matter such as leaf flecks or the like, and which, as a consequence of not having proceeded far in the milling process, has its fibers still entangled and intermeshed to a considerable degree. Such foreign matter, however, if present, is not objectionable, as it is entirely encompassed and hidden by the surrounding veneering. And so, also, with the other materials that may form the core. The interentangled condition of the fibers of the core adds to the toughness and resiliency of the padding as a whole.

50 I have found that the use of asbestos fibers to form the veneering or covering material, is particularly advantageous where padding of high heat-resisting qualities is desired. It will be noted, moreover, that with the padding in which asbestos is used as a veneering, the resiliency and toughness of the padding will be retained for a relatively long period of time by reason of the core of the slivers about which the asbestos veneering is formed, being protected to a large extent from the devitalizing and harmful effects of the heat to which the padding is subjected while in use.

65 In addition to the advantages in use which accrue to the padding made according to my invention, it will be observed that the greater resiliency, and tendency to expand, imparted by the core to the roving, has the advantage, during the knitting operation, of resisting the compressing action of the knitted loops, with the result that the padding when finished, is thicker than paddings, as ordinarily made, of the same weight per square surface area, is more compact by rea-

son of the tendency of the layers to bulge laterally against each other, presents a more fluffy appearance, and tends to expand between the places where it is caught by the knitted loops, so that the latter will in effect be buried in the veneering to a greater extent than with the usual paddings. This is of advantage in increasing the life of the paddings, for it protects the knitted loops from wear.

10 The padding may be manufactured in the form illustrated, or, if desired, it may be made up with a reinforced backing of woven fabric as for instance, in accordance with the patent to Baynard Willingham, No. 1,816,416.

15 Having thus described my invention what I claim as new and desire to secure by U. S. Letters Patent is,

1. The process of preparing a sliver for use in the making of padding for laundry machines, comprising forming a plurality of laps of fibrous materials of different characteristics, one of said materials adapted to comprise the core of the sliver and the other adapted to comprise the covering of the sliver, dividing each of said laps into a plurality of longitudinal strips, assembling 20 on each of a plurality of lap sticks, strips of said different materials with a strip of core material arranged between strips of covering material, feeding the materials so assembled from the lap sticks in a plurality of superimposed layers 25 through a carding machine, dividing the web delivered from the carding machine into sections longitudinally of the web, each section comprising a portion of the core material and a contiguous portion of the covering material, drawing said 30 sections in opposite directions as they are delivered from said carding machine and simultaneously twisting said sections with the core material enveloped within the covering material. 35

2. The process of preparing a sliver for use in the making of padding for laundry machines 40 comprising assembling on each of a plurality of lap sticks in edge to edge relationship a plurality of laps of different materials with the lap comprising the material to form the core of the sliver arranged between the laps comprising the material to form the outer covering of the sliver, feeding the materials so assembled in a plurality of superimposed layers from the lap sticks through a carding machine, dividing the web delivered from the carding machine longitudinally 45 into sections, each comprising a portion adapted to form the core, and a contiguous portion adapted to form the covering of the sliver, and twisting each of said sections with the core portion enveloped within the covering portion. 50

3. The process of preparing a sliver for use in the making of padding for laundry machines comprising assembling a plurality of superimposed layers of different materials, each layer comprising a strip of material adapted to form the core of the sliver, and strips of material adapted to form the outer covering of the sliver arranged on opposite sides of and edge to edge with said first strip, transforming the material so assembled into a web of substantially uniform thickness, dividing the web longitudinally into sections each comprising a portion adapted to form the core, and a contiguous portion adapted to form the covering of the sliver, and twisting each of said sections with the core portion enveloped within 60 the covering portion. 65

JESSE A. HUNT.
